IRONING TABLE

Henry V. Keller, Minneapolis, Minn.

Application February 9, 1931, Serial No. 514,499

5 Claims. (Cl. 68—10)

My present invention relates to ironing tables of the type wherein the ironing board proper is provided with folding or collapsible supporting mechanism attached to the under side thereon ready for use and collapsible compactly for storage or shipment.

Ironing tables of this general class have been extensively utilized and for the most part have included a pair of rear legs pivotally connected to the under side of the board and a third or forward leg also pivoted to the board and inclined or obliquely disposed when the device is set up for use. Various bracing means have been utilized for strengthening the supporting mechanism and reinforcing the legs, usually including diagonally disposed upper braces extending between intermediate points of the rear legs and the medial portion of the board as well as lower brace wires or rods extending between the lower end of the forward leg and medial points on the rear legs.

In most instances the front and rear legs had to be independently set up and the forward ends of the upper braces had to be attached to the board or abutted against a cross piece on the under side of the board before the ironing table could be utilized. Moreover, in such prior structures it was found necessary to either construct the lower brace rods of two folding sections or to make a telescopic or slidable connection at one end of the rod with one of the legs, in either event weakening the lower braces and producing a tendency of the rods to buckle during the setting up or collapsing of the device.

It is an object of my present invention to provide an improved and comparatively inexpensive collapsible ironing table having a maximum amount of rigidity when in use, adapted to be compactly folded for storage or shipment and wherein the entire supporting structure is operatively and automatically set up or collapsed by swinging any one of the legs. All of the parts of the supporting structure are permanently connected to the board or other parts and consequently there is no possibility of the board accidentally collapsing when it has once been set up.

It is the further object of my invention to provide a light but extremely rigid collapsible ironing table wherein the rear supporting legs are automatically spread apart at their outer ends and firmly braced by the action of swinging any one of the legs from the collapsed to the operative position.

It is a more specific object to provide an improved ironing table of the class described where-

in the forward ends of the upper braces are permanently connected with the bottom of the board by a toggle structure adapted to move past a dead center position to lock the legs securely in place when the device is set up and simultaneously tension the various braces for the legs.

Still a further object is to provide an ironing table of the type described wherein the lower brace rods comprise integral elements or rods pivotally connected at their ends with the supporting legs, the distance between the connected points being the same when the legs are either in the collapsed or set up positions thereby obviating the necessity for sectional brace rods or rods having slidable or telescopic connection with the legs.

These and other objects and advantages of the invention will be fully set forth in the following description made in connection with the accompanying drawings, in which like reference characters refer to similar parts throughout the several views, and in which:

Fig. 1 is a perspective view of an embodiment of my invention set up for use;

Fig. 2 is a side elevation of the device in set up position, the dotted lines indicating the position of the upper brace elements prior to passing dead center or locking position;

Fig. 3 is a cross section showing the construction of the braces and hinge elements for the rear legs and taken on the line 3—3 of Fig. 2;

Fig. 4 is a cross section taken on the line 4—4 of Fig. 2 showing the hinge connection between the upper brace bars and the link plate;

Fig. 5 is a bottom plan view of the ironing table in collapsed position, and

Fig. 6 is a horizontal section taken on the line 6—6 of Fig. 2.

In the embodiment of the invention illustrated in the drawings the numeral 7 indicates the flat top or board of the table, which may be of the conventional shape used in ironing boards and having hingedly secured to the rear end thereof the two rear legs 8 which are adapted to lie flush against the bottom of the board when the table is collapsed and which are positioned slightly past vertical when the board is set up for use with the outer ends thereof spread apart to a distance greater than the width of the board. The hinged ends of legs 8 may have inner beveled surfaces 8a engaging the downturned hinge ears 9a of transverse attachment bracket 9 which is rigidly secured to the under side of the rear end of the board. A forward and longer supporting leg 10 is hinged between attachment ears 11

which are secured to the medial portion of the board at the under side thereof. Leg 10 as clearly shown extends in an inclined position when the board is set up and the inner end of the leg 5 is mitered or cut at the proper angle to firmly abut the bottom of the board when the device is set up.

The lower portions of the rear legs 8 are connected together by means of a brace comprising 10 a pair of toggle arms 12, the inner ends of which are pivotally secured to a rear and depending brace arm 13. The outer ends of toggle arms 12 are pivotally connected with short brace arms 12a which are rigidly connected to the legs 8 and 15 which have turned abutment elements 12b adapted to overlie the upper edges of toggle arms 12 and limit the spreading of the outer ends of the legs when the device is set up. The depending or rear brace arm 13 has a twisted upper end 13a 20 which is hinged between angle attachment brackets 13b disposed a short distance forwardly of attachment bracket 9 and centrally of the board.

Upper converging braces connect the medial portions of the rear legs 8 with the medial portion 25 of the board 7 and comprise a pair of diverging brace bars 14 pivotally connected at their lower ends to the inner edges of legs 8 and hingedly connected at their upper and converging ends to a link or locking plate 15, said plate 30 and said brace bars forming a toggle brace which passes the dead center position to lock the legs in set up position and to further tension the legs and brace members. It will be noted that the pivotal connection element (see Fig. 6) upon 35 which locking plate 15 is swingably mounted spans the forward extremities of the brace bars 14 and spaces these extremities apart in a predetermined relation. The forward end of plate 15 is hinged to a bracket 16 disposed some distance 40 from the forward end of the board and at the center of the under side thereof. The forward portions of brace bars 14 are connected by an abutment link 14a which is disposed rearwardly of the inclined forward leg 10 in a position 45 to engage and thrust against the same when the rear legs are swung in the direction of the board for collapsing the table.

A lower brace link connects the intermediate 50 portions of the rear legs 8 with the outer end of the forward or inclined leg and this brace may comprise a pair of converging rods or wires 17 having their rear ends pivotally connected at 17a to the inner sides of legs 8 and having their forward ends pivotally connected at 17b to the outer 55 end of forward leg 10. In the embodiment illustrated the two rods 17 are formed from an integral piece of wire bent into the shape of a V, with the bent end pivoted in the notched portion of the forward portion of the leg 10. 60 Cross pieces or abutment members 18 are secured to the central portion of the bottom of the board and positioned to abut the forward ends of upper brace bars 14 when the table is in set up position. These cross pieces are not absolutely 65 essential, but serve to increase the rigidity of the supporting structure. A locking arm 19 may be pivoted to the board adjacent the link plate 15 adapted to underlie the plate and lock the same in set up position.

70 The compact collapsed position of my table is illustrated in Fig. 5 where it will be seen that the rear legs 8 are disposed substantially flush, edgewise and parallel against the bottom of the board. The upper and lower braces as well as 75 the back brace 13 are also disposed substantially

flush with the board and it will be noted that the beveled inner engagement surfaces at the upper ends of the rear legs 8 are disposed outwardly of the hinge ears 9a of the attachment bracket 9 permitting the outer ends of the rear legs to be drawn inwardly by the collapsing action of the toggle arms 12 connected with rear brace 13.

To set up my ironing table it is only necessary to swing any one of the supporting legs outwardly 10 from the board, the connections between the legs, braces and the board causing all the parts to move in unison to the operative position. The dead center relation of the upper brace comprising brace bars 14 and link 15 may be so adjusted 15 that the impetus of the swinging legs will automatically carry the brace past dead center position into the locked position shown in Fig. 2, thereby placing additional tension upon the brace rods 17 and the legs 8 and 10, or if a maximum 20 tension is desired the toggle pivot of the brace bars 14 and link plate 15 may be adjusted so that some force would have to be exerted to lock the brace in place.

If the forward leg 10 is swung to set up the 25 board, movement will be transmitted to the rear legs and upper brace through the abutment link 14a, thus preventing buckling of the rods 17. It will be noticed that as the rear legs swing outwardly from the board the connection of the 30 rear brace 13 with the toggle arms 12 causes the arms to be swung into substantial alignment, movement thereof being limited by the overlying or turned abutment elements 12b.

If either of the rear legs is swung to set up the 35 board, movement will be transmitted to the forward leg 10 through the engagement of abutting link 14a connected with the upper braces and the parts are swung in unison, as previously described. The swinging of the rear legs brings the 40 beveled or inclined inner surfaces 8a into abutment with the hinge ears 9a of the attachment bracket and thereby permits the outer ends of the rear legs to be spread apart.

To my knowledge I am the first to provide a 45 collapsible ironing table where the upper braces are permanently connected with the bottom of the board and where moreover the lower braces or rods are pivotally connected at their ends to points 17a and 17b with the rear and front legs 50 respectively without the interposition of off-set connections, telescopic joints or flexible or swingable sections connected with the brace rods proper.

The problem was formerly regarded as impossible of solution by ironing board manufacturers due to the fact that the supporting structure included so many different axes or pivots. I have discovered, however, that by constructing 60 the board and positioning the various pivots in the manner illustrated and described the attachment points 17a and 17b of the lower rods or braces may be the same distance apart when the supporting structure is in the collapsed and set 65 up positions and further the forward ends of the brace bars 14 may be permanently connected to the board to permit the entire supporting structure to be automatically set up when any one of the legs is swung.

From the foregoing description it will be seen that I have provided a simple, extremely rigid collapsible ironing table adapted to be very quickly and easily set up or collapsed and incapable of accidental displacement or collapsing of the 75

several parts of the supporting structure when in use.

Attention is called to my improved bracing and hinge construction for the rear legs. This construction is automatically operated by the swinging of any of the supporting legs and also effects the spreading of the rear legs as the table is being set up. It moreover will be seen that in set up position the legs are rigidly held against both outward or inward displacement by the toggle brace arms 12 connected with the rear brace 13.

It will, of course, be understood that various changes may be made in the form, details, proportions and arrangement of the parts without departing from the scope of my invention, which, generally stated, consists in a device capable of carrying out the objects above set forth, and in the novel parts and combinations of parts disclosed and defined in the appended claims.

20 What is claimed is:—

1. In an ironing table, a top, a pair of rear legs pivoted to said top for folding movement thereagainst, a forward leg pivoted to said top forwardly of said rear legs and inclined downwardly and forwardly when the device is set up, an upper brace connecting intermediate portions of said rear legs with an intermediate portion of said top, said brace comprising an elongated section pivoted to said rear legs and extending therefrom to said top when said table is set up and a relatively short section pivoted to said first mentioned section and non-slidably pivoted to said table, said short section lying against the top when the table is set up and a pair of non-collapsible brace rods connecting said forward leg with intermediate points on said rear legs.

2. In an ironing table, a top, a pair of rear legs pivoted to said top for folding movement thereagainst, a forward leg pivoted to said top forwardly of said rear legs and inclined forwardly and downwardly when the device is set up, an upper brace connecting intermediate portions of said rear legs with an intermediate portion of said top, said brace comprising a pair of brace elements, each pivotally connected respectively with one of said rear legs and extending therefrom to said top when said table is set up, said brace elements converging at their forward ends and being pivotally connected with a relatively short element constituting a section of said brace, said short section being pivoted to the top of said table and lying against said top when the table is set up, and a bracing structure connecting said front leg with said rear legs.

3. In an ironing table, a top, a pair of rear legs pivoted to said top for folding movement thereagainst, a forward leg pivoted to said top forwardly of said rear legs and inclined forwardly and downwardly when the device is set up, an upper brace in the form of a two-section toggle connecting intermediate portions of said rear legs with an intermediate portion of said top, one of said toggle sections comprising a pair of forwardly converging brace elements, each pivotally connected respectively with one of said rear legs and both extending from said rear legs to said top when said table is set up, the second of said toggle sections constituting a relatively short rigid plate pivoted between the forward extremities of said converging brace elements and pivoted at its

other end to said table top, the pivotal connections between said rigid plate and said brace elements holding said forward extremities in predetermined spaced relation, said toggle brace construction being proportioned to pass a dead center relationship with reference to the pivotal connections of the toggle with the top and rear legs when the table is set up; and bracing structure connecting said front leg with said rear legs.

4. In an ironing table, a top, a pair of rear legs pivoted to said top for folding movement thereagainst, a forward leg pivoted to said top forwardly of said rear legs and also foldable against said top, and extending in inclined relation to said top forwardly and downwardly when the device is set up, an upper brace connecting the intermediate portions of said rear legs with the intermediate portion of said top and comprising a two-section toggle construction having an elongated section formed of two forwardly converging members each pivotally connected respectively with one of said rear legs and extending therefrom to said top when said table is set up and having a short section pivoted to said elongated section at the forward end of the latter and also pivoted to said table, said forward leg being disposed between said converging brace members, bracing structure connecting said front leg with said rear legs to cause all of said legs to swing in unison after said rear legs have swung a predetermined distance, connections between said rear legs and said top for automatically expanding the free ends of said rear legs when they are swung outwardly into operative position, the point of said connections with said top being offset with respect to a line joining the pivot points of said rear legs and an abutment element traversing said converging brace members adjacent their forward ends and disposed below said forward leg when the table is collapsed and in position to be engaged by said front leg in the initial swinging movement of the front leg from collapsed position to thereby transmit initial swinging movement to said rear legs through said upper brace, to swing said rear legs through said predetermined distance.

5. In an ironing table, a top, a pair of rear legs pivoted to said top for folding movement thereagainst, a forward leg pivoted to said top forwardly of said rear legs and also foldable against said top, an upper brace connecting intermediate portions of said rear legs with said top, said brace comprising an elongated section pivoted to said rear legs and extending therefrom to said top when said table is set up, and a relatively short section pivoted to said first mentioned section and non-slidably pivoted to said table, said short section lying against the top when the table is set up, means including a bracing structure connecting said front leg with said rear legs to cause said rear legs to swing in unison with said front leg when the latter is swung, and connections between said rear legs and said top for automatically expanding the free ends of said rear legs whenever said front leg is swung into operative position, the point of said connections with said top being offset with respect to a line joining the pivot points of said rear legs.

5
